UNITED STATES PATENT OFFICE.

HERMAN L. FAISON, OF WEST PHILADELPHIA, PENNSYLVANIA.

DESIGN FOR A LOUD SPEAKER.

Application filed January 28, 1928. Serial No. 25,073. Term of patent 14 years.

To all whom it may concern:

Be it known that I, HERMAN L. FAISON, a citizen of the United States, residing at West Philadelphia, in the county of Philadelphia and State of Pennsylvania, have invented a new, original, and ornamental Design for a Loud Speaker, of which the following is a specification, reference being had to the accompanying drawing, forming part thereof.

Figure 1 is a side elevation of the loud speaker;

Figure 2 is a front elevation of the loud speaker, facing the horn opening; and

Figure 3 is a sectional view taken on the line 3-3 of Figure 1 and illustrating the cross sectional shape of the front, middle, and back portion of the loud speaker tube.

I claim:

The ornamental design for a loud speaker, as shown.
